Attorneys

UNITED STATES PATENT OFFICE.

JAMES A. WALKER, OF LERNA, ILLINOIS.

SEED-CORN SHELLER.

Application filed February 25, 1922. Serial No. 539,235.

To all whom it may concern:

Be it known that I, JAMES A. WALKER, a citizen of the United States, residing at Lerna, in the county of Coles and State of

5 Illinois, have invented certain new and useful Improvements in Seed-Corn Shellers, of which the following is a specification.

This invention relates to improvements in corn shellers.

10 The primary object of the invention is the provision of an improved device of novel construction, adapted for use in connection with the shelling of seed corn.

A further object of the invention is the 15 provision of a corn sheller, preferably of metallic construction, having the parts thereof constructed of standard materials, in an economical and durable manner.

Other objects and advantages will be 20 apparent during the course of the following detailed description.

In the drawings, forming a part of this 25 specification, and wherein similar reference characters designate corresponding parts throughout the several views;

Figure 1 is a plan view of the improved corn sheller.

Figure 2 is a perspective view of the improved corn sheller, showing the manner in 30 which the same is used in connection with a receptacle, for shelling of seed corn.

Figure 3 is a fragmentary cross sectional view, showing the manner in which the details of the improved corn sheller are relatively assembled.

Figure 4 is an end elevation of the improved corn sheller.

In the drawing, wherein for the purpose of illustration is shown the preferred embodiment of the improved corn sheller, the letter A designates the improved sheller adapted for use in connection with a receptacle B. The improved sheller A preferably comprises a supporting frame portion C, and a seed engaging arrangement D.

The frame C is preferably of sheet metal and bent in channel shape, being preferably U-shaped in cross section so as to provide a relatively flat floor portion 10, having the upstanding legs 12 and 13 upon the sides thereof. The extreme upper edges of the legs 12 and 13 are provided with the flanged over grooves 14 and 15 respectively, which are so bent as to provide pockets 16 facing

each other and extending for the length of 55 said flanges 14 and 15. These pockets or grooves 16 are, in fact, provided for receiving the seed engaging device D.

The device D may be formed of a single piece of rod or wire bent in sinuous formation to provide the spaced parallel bars 19 of practically the same length. By reason of the sinuous construction of the wire forming the device D, adjacent bars or sections 19 are connected at only one end by U-shaped portions 20. The parallel bar portions 19 are preferably all of the same length and arranged so that the U-shaped ends 20, which are in alignment, may be disposed within the pockets or grooves 16 provided 70 in the channel member C. The bars 19 are preferably arcuated downwardly into the channel C so that the convex sides thereof face the bottom or floor 10. In order to maintain the bars 19 in a definite parallel 75 and fixed relation, the flanges 14 and 15 are distorted and crimped, to dispose the edges of the device D therein, and thus permanently and securely attach the channel member C and seed engaging device D together. 80 Thus, the bars 19 are arranged transversely of the channel member C and upwardly of the floor 10 thereof from flange 14 to flange 15. As can readily be seen from Figure 3 of the drawings, the crimps 22 are disposed 85 in the flanges 14 and 15 of the channel member C, in order to maintain the connecting ends of the bar 19 therein.

In operation, the seed corn sheller is disposed in a container B, which is ordinarily 90 provided for reception of shelled corn, in its angular position upon the inside of the container, with one end resting upon the floor 24 of the container and extending upwardly 95 and in an inclined relation to rest upon the top edge 25 thereof. The person desiring to shell corn from the ears, merely places the ears so that the seeds thereof are in engagement with the concaved sides of the parallel bars 19, and by drawing upwardly 100 or reciprocating the ear over the device D, the grains or seeds of the ear will become dislodged and fall intermediate the bars onto the floor 10 of the channel. Due to the inclined position of the floor 10, the grains or seeds will naturally fall upon the bottom 105 24 or inside of the container B.

Various changes may be made to the shape,

size, and arrangement of parts of the form of the improved seed corn sheller herein shown and described without departing from the spirit of the invention or the scope 5 of the claims.

I claim:

1. A corn sheller comprising a channel shaped member of sheet metal bent in substantially U-shaped manner to provide outward standing legs, and a seed engaging device including spaced bars affixed to and extending transversely between the free ends of said outstanding legs.
2. In a device of the class described, the combination of a supporting member formed of sheet metal into channel shape and including a floor with upstanding sides, the free edges of said sides having flanges thereon providing longitudinal grooves, and a sinuously bent seed engaging member formed of wire to provide a plurality of substantially parallel bar portions arcuately formed, the lateral edges of said seed engaging device adapted for being positioned 25 in the grooves of said channel shaped member and crimped therein, whereby the con-

20 vex sides of said bar portions face the floor of said channel member.

3. A shelling device comprising a substantially U-shaped channel frame, and bars rigidly affixed at their ends in the side marginal portions of said frame, said bars being concavo-convex as to their length and so affixed to said frame that the convex sides thereof face inwardly of the pocket of said 35 U-shaped channel frame.

4. A corn shelling device comprising a channel shaped frame of U-shaped formation including a floor portion and upstanding side portions, the upstanding side portions having outwardly extending pocket shaped flanges thereon, and a sinuously bent wire member providing a plurality of spaced bars which are adjacently connected at their ends by U-shaped portions, said U-shaped portions being disposed in the pocket shaped flanges of said frame and fixedly crimped therein so that the bars are affixed at their ends in said frame and extend in spaced relation over 40 45 50 said floor.

JAMES A. WALKER.
